UNITED STATES PATENT OFFICE

2,521,832

COMPOST TURNING MACHINE

Guy J. Cordivano, Kennett Square, Pa.

Application June 14, 1946, Serial No. 676,798

2 Claims. (Cl. 212—44)

1

The present invention relates to compost manipulating machines and more particularly to a machine for turning, aerating and rebuilding composts, which is necessary in order to properly cure the compost material, this being especially desirable in connection with the raising of mushroom rooms.

An important object of the invention is to provide an apparatus adapted to bite into a compost pile, lift a quantity of the material to an elevator from where it is discharged onto a rapidly rotating cylinder, which breaks up the compost material, at the same time aerating the same in the course of building up another compost pile.

Another object of the invention is to provide a machine for moving the material of compost piles, in the course of which removal, the material is thoroughly broken up and aerated.

Still another object of the invention is to provide a machine of the character stated which while being positive acting and substantially fool-proof in all respects, is of simple construction and not too costly to manufacture for retail to small operators in the mushroom business and in fact in other lines where compost material is a necessity.

A further object of the invention is to provide a machine of the character stated which will operate rapidly and save considerable time and expense, that is at present required, in properly breaking up and aerating compost.

These and various other objects and advantages of the invention will become apparent to the reader of the following description.

In the drawings:

Figure 1 is a side elevational view of the machine, mounted on a wheeled carriage;

Figure 2 is a side elevational view of the machine with parts in section and fragmentary showing the boom;

Figure 3 is a fragmentary top plan view of the boom and claw fork;

Figure 4 is a cross sectional view taken on line 4—4 of Figure 2;

Figure 5 is a cross sectional view through the elevator taken on line 5—5 of Figure 1;

Figure 6 is a diagrammatic view showing the hydraulic means for both the claw fork and boom.

Referring to the drawings, numeral 5 generally refers to a boom, which elevates or lowers a claw fork generally referred to by numeral 6. An elevator generally referred to by numeral 7 is also used in conjunction with the boom and fork, as is a rotary drum 8, and the details of these items will now be specifically set forth.

2

The boom 5 includes a pair of elongated steel fabricated arms 9, each of which has its inner end suitably secured as at 10 to a corresponding end of a crank shaft 11 which is journaled through bearings 12 supported by horizontal beams 13 in an upstanding frame 14, supported on the chassis 15 of a wheeled carriage 16, which may be motor driven or pulled by a tractor.

The outer ends of the boom arms 9 (see Figure 10) 3 have openings or bearings into which the ends of a bar 17 project and to which the arms are secured.

The claw fork 6 is swingable on this bar 17 and includes arms 18, which diverge downwardly, as 15 in the manner shown in Figure 1.

A hydraulic cylinder 19 has an apertured ear 20 at its upper end for receiving the bar 17, while the plunger therein has an extension, attached as at 20' to an underlying bar 21, the latter bar 20 extending through arcuate slots 22 in arms 23 which extend inwardly to overlapping position from time assemblies or forks 24, these forks 24 each having back bar *a* and tines *b*. These forks are swingably mounted between the lower ends 25 of the arms 18. Thus it can be seen that when the piston in the cylinder 19 is forced downwardly, the arms 23 will be urged downwardly, swinging the forks 24 outwardly to open position as shown in dotted lines in Figure 1.

The upper portion of the frame 14 (see Figure 2) has an inwardly projecting structure 25 to which the upper end of a second hydraulic cylinder 26 is pivoted, this cylinder having a piston 27 therein, from which a rod 28 extends to pass through the open end of the cylinder and connected by a bearing 29 to the crank portion 30 of the crank shaft 11, this shaft having the booms 9 connected to the ends thereof. Obviously, operation of the hydraulic cylinder 26 will result 40 in the elevating and lowering of the boom assembly 5.

Frame members 31 project rearwardly from the frame 14 adjacent the upper portion thereof and are braced by inclined members 32.

On the frame members 31 are bearings 33 through which a shaft 34 is disposed, and to this shaft, and rotating between the frame members 31, is a drum 35, having a plurality of longitudinally extending and outstanding cleats 36 suitably secured thereto. One end of the shaft 34 carries a sprocket wheel 37 over which a sprocket chain 38 is trained, and this chain also extends over a larger sprocket wheel 39 located on a shaft 40.

The elevator 7 is mounted within side walls 41 and includes the upper shaft 40 and a lower

shaft 42, on each of which are sprocket wheels 43 over which conveyor chains 44 are trained, these chains being bridged by upstanding cleats or carrier bars 45 for carrying material upwardly and out through the upper end of a hopper 46, to drop onto the drum 8. The hopper 46 has its lower end built up by wider wall 47, to afford depth in which a considerable quantity of the compost material can repose as it is being fed up from underneath, to the discharge end of the elevator. Of course the lower end of the hopper 46 is closed.

As is shown in Figure 6, a valvular control 48 is provided for the fork 6, and a valvular control 49 is provided for the boom 5, each of these controls has a handle. A pump 50 supplies hydraulic pressure by way of a conduit 51 to the controls 48, 49. The hydraulic cylinders 19 and 26, for the fork 6 and boom 9, respectively, have pipe connections 52, 53 for each, and there is a return pipe from each of the control valves 48, 49, denoted by numeral 54 to the pump 50.

It can now be seen, in the operation of the machine, that the apparatus is driven adjacent to a pile of compost where the fork 6 can conveniently reach the material. By now manipulating the control 49, the boom 9 can be lowered rapidly (and this with the fork 6 in open position) so as to drive the tines of the fork into the compost material. By now actuating the control 48, the fork is closed around a load of material. The control 49 is now actuated, charging the cylinder 26 with hydraulic pressure, which results in the rotation of the crank shaft 11 and the lifting of the boom and claw fork to the elevated position, shown by dotted lines in Figure 1: The control 48, for the cylinder 19 is now actuated for the purpose of opening the fork structure 6, with the result that the load is dumped into the hopper 46. Inasmuch as the elevator 7 is in operation, the cleats 46 will catch the compost material and carry it upwardly until it is discharged over the upper end of the elevator and onto the rapidly rotating cylinder 8, where the material is struck with considerable force by the cleats 36, breaking the material and incidentally aerating the same as it is thrown through the air in the act of forming another compost pile.

The boom is again lowered to secure another load and elevated to the dotted line position as shown in Figure 1 and this can be continued almost as rapidly as the boom 5 can be actuated, inasmuch as the elevator 7 will remove the material to the cylinder 8 quite rapidly.

When all of the compost material within range of the fork 6 has been secured, the machine can be manipulated to a point where the fork will again be within range of the material to be lifted, aerated and repiled.

Obviously, the apparatus can be mounted directly on a tractor, so that the resetting of the machine can be done quickly at a saving in time and labor.

It is also apparent that the parts of the apparatus are readily accessible and capable of being reached at all times for the purpose of lubricating, repairs or replacements.

While the foregoing description sets forth the invention in specific terms, it is to be understood that numerous changes in the shape, size and materials may be resorted to without departing from the spirit and scope of the invention as claimed hereinafter.

Having described the invention what is claimed as new is:

1. In a compost distributing machine, a portable frame, a crank shaft rotatably mounted and extending longitudinally of the frame and having a crank intermediate its length, a boom having side bars secured at inner ends to said crank shaft and having vertical swinging movement from a horizontally extending lowered position to a raised position over the frame, a supporting rod extending between and carried by outer ends of the side bars, a claw-fork pivotally suspended from said rod between the side bars and having jaws pivotally mounted for swinging movement from a closed position to an opened position, operating arms for the jaws extending toward each other, a cylinder suspended from said rod, a piston operating in the cylinder and connected with the arms of the jaws for swinging the jaws to the opened position when the piston is moved downwardly in the cylinder, a second cylinder mounted vertically in said frame above the crank shaft, and a piston operating in the second cylinder and having its piston rod projecting from the lower end thereof and connected with the crank of the crank shaft for rotating the said crank shaft and swinging the boom and the fork upwardly to a raised position.
2. In a compost distributing machine, a portable frame, a crank shaft extending longitudinally of the frame and rotatably mounted, a boom having side bars secured at inner ends to the crank shaft, a fork mounted between the outer ends of said side bars, a cylinder in said frame mounted above the crank shaft and extending downwardly at an incline toward the crank of the crank shaft, and a piston operating in said cylinder and having its piston rod projecting from the bottom of the cylinder and connected with the crank of the crank shaft for imparting rotary motion to the crank shaft and swinging the boom upwardly to a vertical position over the frame when the piston is moved downwardly in the cylinder.

GUY J. CORDIVANO.
